MOBILE BASE FOR MINING MACHINES

Joseph F. Joy, Pittsburgh, Pa., assignor to Joy Manufacturing Company, Pittsburgh, Pa., a corporation of Pennsylvania

Original application February 1, 1947, Serial No. 725,950, now Patent No. 2,801,093, dated July 30, 1957. Divided and this application January 25, 1954, Serial No. 405,894

3 Claims. (Cl. 262—1)

This invention relates to mining machines and more particularly to an improved mobile base structure for such a machine whereby the latter may be fed over the mine floor and steered either to the right or left.

An object of the present invention is to provide an improved supporting and mobility providing means for a mining machine. Another object is to provide a mobile base structure for moving the mining machine over the floor of a mine and for steering the machine. A further object is to provide an improved creeper or walking base structure. A still further object is to provide an improved walking base structure having improved means for effecting steering of the base. These and other objects and advantages of the invention will, however, hereinafter more fully appear.

This application is a division of my copending application Serial No. 725,950 filed February 1, 1947, and since issued as Patent No. 2,801,093 dated July 30, 1957. In the accompanying drawings there is shown for purposes of illustration one form which the invention may assume in practice.

In these drawings:

Fig. 1 is a side elevational view of a mining machine having a mobile base structure constructed in accordance with an illustrative embodiment of the invention, showing the machine in operating position in a mine.

Fig. 2 is a top plan view of the mining machine shown in Fig. 1.

Fig. 3 is an enlarged plan view of the mining machine with parts arranged in a compact manner for movement about the mine, and showing parts of the mobile base in horizontal section.

Fig. 4 is an enlarged cross section taken on line 4—4 of Fig. 3.

Figs. 5 and 6 are somewhat diagrammatic side views with parts of the mobile base shown in vertical section, illustrating the manner of operation of the base.

Fig. 7 is a diagrammatic plan view illustrating the manner of turning or steering the base during its movement over the mine floor.

Fig. 8 is a diagrammatic view illustrating the hydraulic fluid system.

In this illustrative embodiment of the invention an improved mobile base, generally designated 1, is shown embodied in a coal mining machine, generally designated 2. The mining machine may assume various forms but is herein preferably of the longwall, floor type slideable on its bottom over the floor of a mine. Evidently the mobile base may be incorporated in machines of other types.

The mining machine 2 herein comprises, as shown in Figs. 1 and 2, a main frame or body 3 which supports, at its forward end, a pair of universally adjustable, coacting kerf cutting devices 4 and drilling and dislodging mechanism, generally designated 5. The frame or body 3 is supported on the improved base 1 which includes a bottom base member or floor engaging skid 6 resting upon and slideable in any direction over the mine floor. Carried by relatively movable parts of this sliding base or skid

2

are pairs of upstanding roof-engaging jacks or anchor devices 7 and 8, respectively positioned at the forward and rearward ends of the machine body, and the machine body is suitably supported by the base as by the front jacks 7 and as by upstanding platelike side supports 9 arranged at the rear sides of the machine body at the inner sides of the rear jacks 8, as shown most clearly in Figs. 3 and 4.

The front roof jacks 7 comprise vertical double acting fluid cylinders 10 suitably fixed to the base and projecting upwardly along the sides of the machine body, and the latter has lateral lugs 11 suitably attached to these cylinders near their upper ends. Reciprocable in the cylinders are pistons 12 having their piston rods 13 projecting upwardly through the top cylinder heads and carrying at their upper ends, roof-engaging abutments 14. The rear roof jacks 8 have vertical double acting cylinders 15 (Figs. 3 and 4) suitably fixed to longitudinally elongated, relatively narrow, horizontal slides 16 (Fig. 5) constituting parts of the base and guided in parallel longitudinally extending guideways 17, herein formed at the sides of the main part of the base at the outer sides of the machine body. Secured to the bottoms of the rear portions of these slides are floor-engaging abutments 18. The cylinders 15 contain reciprocable pistons 19 having their piston rods 20 projecting upwardly through the top cylinder heads and carry, at their upper ends, roof-engaging abutments 21. The jack pistons 12 and 19 are movable upwardly under the influence of pressure fluid in the cylinders 10 and 15 to bring the abutments 14 and 21 firmly into engagement with the mine roof.

Extending longitudinally at the sides of the base member 6 are horizontal jacks of feed rams 22 comprising horizontal double acting fluid cylinders 23 (see Fig. 3) arranged above and parallel with the guideways 17 and 35 suitably fixed to the base member 6. Reciprocable in these cylinders are pistons 24 having their piston rods 23' projecting rearwardly through the rear cylinder heads and suitably rigidly attached at 24' to the vertical cylinders 15 of the rear roof jacks 8.

40 When the rear roof jacks are held in firm engagement with the mine roof, with the bottom abutments 18 held firmly in engagement with the mine floor, and the front roof jacks 7 are released, the feed cylinders 23 may be moved forwardly under the influence of pressure fluid relative to the then-stationary pistons 24 thereby to move the base member 6 and the mechanism carried thereby, forwardly over the mine floor toward the working face. When the front roof jacks 7 are held in firm engagement with the mine roof and the rear roof jacks 8 are released, the pistons 24 may be moved forwardly under the influence of pressure fluid relative to the then-stationary cylinders 23 thereby to move the rear roof jacks again into their foremost position. When the slides 16 are in their extended position (Fig. 5) and are held stationary by the 55 rear roof jacks 8, and the front roof jacks 7 are released, the feed cylinders may be moved rearwardly under the influence of pressure fluid relative to the then-stationary pistons 24, moving the base member 6 and the mechanism carried thereby, rearwardly in a direction away from the working face. From the foregoing, it will be evident that the mining machine may be walked step by step either rearwardly or forwardly by suitable operations of the front and rear roof jacks and the horizontal feed jack.

Now referring to the hydraulic fluid system, shown 65 diagrammatically in Fig. 8, for supplying fluid under pressure to the various hydraulic cylinders of the machine, it will be observed that a conventional motor driven pump 25 has its intake connected by a conduit 26 to a reservoir 27 which preferably contains a liquid. The pump discharge is connected by a conduit 28 to the inlet passageway of a conventional control valve mechanism 29 and the discharge passage of this valve mechanism

is connected by a return conduit 30 back to the reservoir. The valve mechanism has a valve box 31 provided with parallel bores for respectively receiving control valves 32, 33, 34, 35 and 36, each having a suitable operating handle. The bores containing the valves 32 and 33 are respectively connected by pairs of conduits 37, 38 and 39, 40 to the opposite ends of the fluid cylinders 15 respectively of the rear jacks 8. The bores containing the valves 34 and 35 are respectively connected by pairs of conduits 41, 42 and 43, 44 to the opposite ends of the horizontal feed cylinders 23 respectively. The bore containing the valve 36 is connected by conduits 45 and 46 to the opposite ends of the fluid cylinders 10 of the front roof jacks 7. It will thus be seen that the rear jack and feed cylinder at one side of the machine and the rear jack and feed cylinder at the opposite side of the machine have independency of control, thereby to provide greater flexibility in the steering of the machine, as will later become apparent.

When the machine is located at the working face, as shown in Figs. 1 and 2, the cutting devices 4 and the drilling and dislodging mechanism 5 may be operated to cut the mineral of the solid mine vein and to dislodge the mineral in manners fully disclosed in the copending application above referred to, and when it is desired to advance the machine the fluid cylinders 15 of the rear roof jacks 8 may be operated, under the control of the valves 32 and 33, thereby to hold the slides 16 in a stationary position with the bottom abutments 18 firmly engaging the mine floor. The feed cylinders 23 may then be concurrently operated, under the control of valves 34 and 35, to feed the base 6 and the cutting and dislodging mechanism carried thereby, bodily toward the working face to feed the cutting devices into the mineral and the fluid cylinders 10 of the front roof jacks 7 may then be operated, under the control of the valve 36, to engage the front jacks with the mine roof thereby to hold the machine in a stationary position; and the cutting and dislodging devices may then again be operated to cut and dislodge the mineral. While the machine is held stationary by the front roof jacks 7, the feed cylinders 23 may be operated to move the slides 16 together with the released roof jacks 8, again into their foremost position, so that the mining machine may again be fed forwardly.

During tramping of the machine about the mine, the drilling and dislodging mechanism 5 is fully retracted and the kerf cutting devices may be moved into the compact folded position shown in Fig. 3 and the front and rear roof jacks 7 and 8 and the horizontal feed jacks 22 may be operated in the manner above described, to advance the machine step by step over the mine floor. When steering of the machine either to the right or left is desired, the rear roof jacks and the feed jacks may be independently operated to effect sliding of the base member 6 laterally in one direction or the other as desired.

As shown diagrammatically in Fig. 7 the steering of the machine toward the left as the machine is advanced is shown, and during this steering operation only the rear roof jack 8, shown in the nearer left hand end of the machine, is held in firm engagement with the mine roof with the other rear roof jack and the front roof jacks held released. During this operation the far feed jack 22 is maintained inoperative and the near feed jack 22 is operated, under the control of the valve 35, to move the near feed cylinder 23 forwardly under the influence of pressure fluid thereby to feed the base member together with the cutting and dislodging mechanisms carried thereby, forwardly over the mine floor and during this operation as the base member is advanced, it is slued or swung laterally toward the left to bring the parts into the dotted line position shown in Fig. 7. The near rear roof jack 8 is then released and together with the associated slide 16 is fed forwardly and thereafter the jack may be extended into firm engagement with the roof. These operations

may be successively repeated thereby to feed the machine forwardly step by step toward the left through a wide arc. If steering of the machine toward the right is desired, the opposite rear roof and feed jacks may be operated as above described while the other jacks are maintained released. Thus the machine may be moved step by step either forwardly or rearwardly along the mine floor and turned horizontally either to the right or to the left as desired.

As a result of this invention, an improved mobile base is provided for a mining machine whereby the machine may be walked step by step and may be steered in an improved manner. By the provision of the improved roof and feed jack structure and the separate control valves for the feed jacks and the rear roof jacks, not only may the machine be fed along a straight path but may also readily be steered along a curved path either to the right or left as desired. The improved base structure embodying the separate slides and guideways at the opposite sides of the base together with the associated roof and feed jacks, provide a mobile base which is not only extremely flexible in operation but is also relatively simple and rugged in design, well adapted for its intended purpose. These and other advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In an apparatus of the character disclosed, a walking base for advancing and steering the apparatus, said base having a bottom skid plate which receives the weight of the apparatus, said skid plate providing parallel longitudinally extending guideways at the sides thereof, narrow elongated slides received in said guideways respectively, a pair of upright roof jacks mounted at the forward portion of said skid plate at the sides of the latter, a pair of upright rear roof jacks respectively secured to the rear portions of said slides for separately holding the latter stationary and parallel feed jacks extending longitudinally at the sides of said skid plate and operatively connected to said rear roof jacks and to said skid plate for moving said slides along said guideways when said skid plate is held stationary by said front roof jacks, said feed jacks when said slides are held stationary by said rear jacks effecting advance of said skid plate relative to said slides, means for controlling said front jacks to apply or release the same, and means for separately effecting operation of said rear roof jacks and said feed jacks while said front jacks are released to effect turning of the machine either to the right or left as said skid plate is advanced.

2. In an apparatus of the character disclosed, a walking base having a bottom skid plate for receiving the weight of the apparatus and adapted to rest upon and move in any direction over the mine floor, said skid plate providing parallel longitudinally extending guideways at the sides thereof, narrow elongated floor engaging slides received in said guideways, a pair of upright front roof jacks mounted on said skid plate at the sides at the forward portion thereof, a pair of upright rear roof jacks respectively secured to the rear portions of said slides for securing the latter in stationary position with respect to the floor, and parallel feed jacks extending longitudinally at the sides of said skid plate and operatively connected to said rear roof jacks and said skid plate for moving said slides along said guideways when said skid plate is held stationary by said front roof jacks, said feed jacks when said slides are held stationary by said rear jacks effecting advance of said skid plate relative to said

slides, said rear roof jacks and said feed jacks having power operating means, and separate controls for said power operating means for said rear roof jacks and said feed jacks for effecting operation of said rear roof and feed jacks at one side of the machine independently of said rear roof and feed jacks at the other side thereof.

3. In an apparatus of the character disclosed, a base member for receiving the weight of the apparatus and movable over the floor of a mine, said base member providing parallel longitudinally extending guideways at the sides thereof, narrow elongated slides received in said guideways respectively, front roof jacks mounted on said base member at the sides thereof, rear roof jacks connected to the rear ends of said slides respectively, and parallel longitudinally extending feed jacks operatively connected to said base member and to said slides for advancing said base member relative to said slides when the latter are held stationary by said rear roof jacks and for advancing said slides relative to said base mem-

ber when the latter is held stationary by said front roof jacks, said rear roof jacks and said feed jacks having power operating means, and separate controls for said power operating means for said rear roof jacks and said feed jacks for operating said rear roof and feed jacks at one side of the base member independently of the rear roof and feed jacks at the other side thereof to effect lateral turning of said base member as the latter is advanced.
